UNITED STATES PATENT OFFICE.

JOSEPH ELMER, OF CHICAGO, ILLINOIS.

SECTIONAL RADIATOR TUBE, CONNECTOR, EXPANDER, AND FLANGER.

1,119,416.

Specification of Letters Patent.

Patented Dec. 1, 1914.

Application filed November 18, 1912. Serial No. 732,031.

To all whom it may concern:

Be it known that I, JOSEPH ELMER, a citizen of the United States, residing at Chicago, in the county of Cook and State of Illinois, have invented a certain new and useful Improvement in Sectional Radiator Tubes, Connectors, Expanders, and Flangers, of which the following is a specification.

This invention relates to radiator connector expanders and the like, and has for its object to provide a new and improved device of this description:

The invention is illustrated in the accompanying drawings, wherein—

Figure 1 is a view of a radiator with parts broken away showing the connection between the sections when completed; Fig. 2 is a sectional view showing the device in position ready to complete the connection; Fig. 3 is a sectional view similar to Fig. 2 showing the parts after the device has been expanded; Fig. 4 is a sectional view taken on line 4—4 of Fig. 3. Fig. 5 is a detail of the end piece.

Like numerals refer to like parts throughout the several figures.

Referring now to the accompanying drawings, I have shown a radiator 1 made up of a series of sections 2. These sections are connected together by means of short tubes 3. The tubes are expanded and have their ends flanged so as to produce a tight joint. In Fig. 2, I have shown an enlarged view in section with the tube and expanding device in position therein ready to be operated. This expanding device consists of two segment separate pieces 4 and 5, separate from each other and provided at their ends with the enlarged or projecting portions 6 connected with the body of the pieces 4 and 5 by means of the inclined faces 7. The pieces 4 and 5 are hollowed out so as to provide the grooves 8. An expanding piece 8 is mounted upon a controlling rod or part 9 and is provided with a beveled face 10 adapted to be forced between the pieces 4 and 5. The part 9 is preferably non-circular so that a wrench may be applied thereto. Some means is provided for holding the pieces 4 and 5 in position while the tool is being moved into the short tube 3. Any suitable means for this purpose may be used. As herein shown, the part 9 is provided with an end piece 11 small enough to be inserted in the tube. The holding pieces 12 are inserted in the openings in the pieces 4

and 5 and are movably connected with the end piece 11 so that they can be spread apart as the pieces 4 and 5 are spread apart. As herein shown, the holding pieces 12 are provided with reduced portions which work in slots 13 in the end piece 11. The expanding piece 8 is preferably provided with guides or wings 14 which pass between the pieces 4 and 5 as shown in Fig. 4 so that said pieces will be rotated when the part 9 is rotated. When it is desired to connect two radiator sections together for example, the short tube 3 is placed in position in the openings in the sections and the pieces 4 and 5 inserted therein as shown in Fig. 2. In this position the portion of the part 9 between said pieces is small so as to let them come together a sufficient amount to permit them to be inserted in the tube. The expanding device 8 is now forced in between the pieces 4 and 5 so as to spread them apart and the expanding device and part 9 are rotated so as to expand and flange the ends of the tube 3 and as it were rivet them to the radiator sections so as to provide a tight connection between said sections, the parts being in their expanded position with the connection completed as shown in Fig. 3. After the ends of the tube 3 have been properly expanded and flanged, the expanding device 8 is removed from the pieces 4 and 5 and the tool withdrawn from the tube. It will thus be seen that by means of this construction, the radiator sections may be easily, quickly and cheaply connected together by means of a simple but yet tight and secure connection, without the use of screw threads, gaskets or bolts, and by means of a simple short section of a connecting pipe or tube. This device connects the sections together without undue or uneven strains being developed thereby preventing injury to the parts.

In Figs. 2 and 3, I have shown beveled end faces on the two radiator sections, but it is of course evident that this is not necessary and that the device may be applied to the ordinary sections without these inclined faces and where the portion around the openings is of any ordinary form and construction.

I claim:

1. A sectional radiator tube, connector, expander and flanger comprising two separable segment parts adapted to be inserted in a connecting tube between the sections

or pass through therein, said parts provided at their ends with projections connected to the main body thereof by inclined faces for simultaneously flanging two internal ends of said tube, an expanding device adapted to be forced between said separable parts while in position, so as to separate them, thereby expanding and flanging the said tube and at the same time clamping the section together.

2. A sectional radiator tube, connector, expander and flanger comprising two separable segment parts adapted to be inserted in a connecting tube between the sections, said parts provided at their ends with projections connected to the main body thereof by inclined faces, a rod which passes between said separable parts provided with a small portion which permits the two separable parts to come close together and a larger expanding portion, means for connecting said separable parts with said rod, said larger expanding portion adapted to be forced between said parts while in position so as to separate them and means for rotating said separable parts so as to expand the ends of said tube and tightly connect it with the radiator sections.

3. A sectional radiator tube, connector, expander and flanger comprising two separable segment parts adapted to be inserted in the short tube between the radiator sections, said parts having enlarged ends connected to the body portion by inclined faces, a controlling part passing between said separable parts and to which they are movably connected, an expanding part connected with said controlling part and adapted to be forced between said separable parts so as to spread them apart.

4. A sectional radiator tube, connector, expander and flanger comprising two separable segment parts adapted to be inserted in the short tube between the radiator sections, said parts having enlarged ends con-

nected to the body portion by inclined faces, a controlling part passing between said separable parts and to which they are movably connected, an expanding part connected with said controlling part and adapted to be forced between said separable parts so as to spread them apart, and means for rotating said separable parts when spread apart.

5. A sectional radiator tube, connector, expander and flanger comprising two separable segment parts having enlarged ends, said separable parts provided with grooves on their adjacent faces, a controlling device adapted to pass into said grooves comprising two parts, one larger in size than the other, the larger part adapted when forced between said separable parts to separate them, an end piece connected with said controlling device, and connecting pieces movably connected with said end pieces and engaging said separable parts.

6. A sectional radiator tube, connector, expander and flanger comprising two separable segment parts having enlarged ends, said separable parts provided with grooves on their adjacent faces, a controlling device adapted to pass into said grooves comprising two parts, one larger in size than the other, the larger part adapted when forced between said separable parts to separate them, said enlarged part provided with laterally projecting guides which project beyond said grooves and between said separable parts, an end piece connected with said controlling device, and connecting pieces movably connected with said end piece and engaging said separable parts.

In testimony whereof, I affix my signature in the presence of two witnesses this 12th day of November 1912.

JOSEPH ELGER.
